UNITED STATES PATENT OFFICE.

EDWARD L. SIMONS, OF LANSDOWNE, PENNSYLVANIA, ASSIGNOR OF ONE-HALF TO
HENRY ENEU JOHNSON, OF LANSDOWNE, PENNSYLVANIA.

ELECTRIC FIXTURE.

1,062,555.

Specification of Letters Patent. Patented May 20, 1913.

Application filed October 1, 1912. Serial No. 723,296.

To all whom it may concern:

Be it known that I, EDWARD L. SIMONS, a citizen of the United States, and a resident of Lansdowne, in the county of Delaware and State of Pennsylvania, have invented certain new and useful Improvements in Electric Fixtures, of which the following is a specification.

My invention relates to improvements in electrical fixtures and the object of my invention is to furnish a portable electric fixture which by the simple substitution of parts, will be equally adapted for the lighting of a cigar or cigarette or for a trouble lamp.

My invention is designed primarily for use in connection with automobiles or motor boats, it will be understood, however, that I do not desire to limit myself to its use in any particular connection for it will be apparent that it may be of very general application.

In the accompanying drawings, in which similar letters of reference indicate similar parts throughout the several views:—Figure 1, is a central longitudinal sectional view of my electrical fixture carrying a cigar or cigarette lighter: Fig. 2, a similar view of the fixture carrying an electric light: Fig. 3, a side elevation of the fixture and a keeper for carrying it: Fig. 4, a front elevation of Fig. 1.

5 is a shell, preferably but not necessarily, of cylindrical shape constructed of some insulating material as hard rubber, wood, fiber, etc. The shell is of short length and small diameter and at one end carries a socket 6 of metal which is held in place by a perforated screw plug 7 the exteriorly threaded stem 8 of which is screwed into the base of socket 6 which passes into a hole formed in the end wall of the shell 5 and the head 9 of which engages the outer side of the end wall as shown.

45 The socket 6 carries interiorly a porcelain washer 10 to which is attached an electrical contact 11, adapted to be secured to a line wire 12, and a threaded neck 13 adapted to carry interchangeably a box 14 carrying a

resistance coil 15, Figs. 1 and 4, or an electric lamp 16, Fig. 2, either one of which may be screwed into or out of the neck 13 as may be desired.

16 is a flat spring one end of which is in electrical connection with the metallic part 55 of socket 9, which is in electrical connection with the second line wire 17, and 18 is a push button which being pressed engages the metal frame of resistance coil 14 and establishes a current in the fine wire 19 one 60 end of which is connected to the metal part of the metal frame of box 14 and the other end of which is in engagement with electrical contact 11 connected to the first line wire 12, or with one pole of an electric lamp 65 20 the other pole of which is in contact with contact 11 and first line wire 12. The button 18 being pushed in causes spring 16 to establish an electric current through the coil 15 or the filament of the lamp 20.

70 21, Fig. 3 is a spring socket for carrying the fixture when it is not in use.

22 is an annular ridge around the shell 5 for the arms of the socket 21 to engage as shown in Fig. 3.

75 Having thus described my invention I claim as new and desire to secure by Letters Patent:—

In an electrical fixture, in combination, a shell of insulating material, a metallic 80 socket carried by the interior of said shell, an electrical connection one pole of which is carried by but insulated from said socket, a spring carried by said socket and in electrical connection with the other pole of the 85 electrical connection, an electrically operated device adapted to be removably carried by the neck of said socket one pole of which is in contact with the pole carried by and insulated from said socket, and a means where- 90 by said spring may be moved at will into contact with the other pole of said device in order to complete the circuit.

EDWARD L. SIMONS.
